WEDDING RING

Abraham G. Sager, 910 W. Jackson Blvd., Chicago, Ill.

Filed Dec. 23, 1964, Ser. No. 83,134

Term of patent 14 years

(Cl. D45—10)

Fig. 1

Fig. 2

Fig. 3

FIGURE 1 is a front perspective view of a wedding ring showing my new design;

FIGURE 2 is a top plan view of the wedding ring; and

FIGURE 3 is a side elevation of the wedding ring.

My design for a wedding ring is characterized by a circular contour graduated from the rear to a wider front with a narrow plain outer front raised marquise plateau, the ends of which are confined within the circular edges of the ring, the sides of the ring each having a brushed metal finish conforming to the adjacent curved side of the marquise plateau and terminating short of the peripheral rear surface in angular points between which the surface is polished metal.

I claim:

The ornamental design for a wedding ring, as shown and described.
